UNITED STATES PATENT OFFICE.

JOHN PIERCE, JR., OF NORWALK, CONNECTICUT, ASSIGNOR OF ONE-HALF TO
DICKINSON S. CUMMINGS, OF STAMFORD, CONNECTICUT.

GAS-TIGHT JOINT FOR BOILER CASINGS REMOVABLY MOUNTED UPON FIREPOTS.

Application filed March 16, 1923. Serial No. 625,497.

To all whom it may concern:

Be it known that I, JOHN PIERCE, Jr., a citizen of the United States, residing at Norwalk, in the county of Fairfield and 5 State of Connecticut, have invented a new and useful Improvement in Gas-Tight Joints for Boiler Casings Removably Mounted upon Firepots; and I do hereby declare the following, when taken in connection with the accompanying drawings and the characters of reference marked thereon, to be a full, clear, and exact description of the same, and which said drawings constitute part of this application, and 10 represent, in—

Fig. 1 a view in side elevation of a firepot having a removable boiler-casing mounted upon it, the joint between the two parts being constructed in accordance with my 15 invention.

Fig. 2 an enlarged broken sectional view on the line 2—2 of Fig. 1.

Fig. 3 a broken plain view, on the scale of Fig. 2, of one corner of the firepot.

20 My invention relates to an improved gas-tight joint for that class of boiler-casings which are removably mounted upon the firepots of the steam-generating units of steam automobiles, tractors, airplanes, road-rollers, etc., the object being to insure a gas-tight joint between the removable boiler-casing and the firepot, no matter how frequent the occasion to remove the casing.

With these ends in view, my invention 25 consists in certain details of construction as will be hereinafter described and particularly pointed out in the claims.

In carrying out my invention, as herein shown, I employ a boiler-casing consisting 30 of a sheet-metal shell 5 having a lining 6 of insulating and refractory material, the lower end of which is beveled, as at 7, to complement the bevel 8 formed at the upper end of the insulating and refractory lining 9 of the firepot, which has a sheet-metal shell 10. The lower edge of the shell 5 is carried below the lower point of the bevel 7 to form a flexible sealing-flange 11, which is intended to sleeve over, with a relatively 35 snug fit, the bent upper edge 12 of the firepot shell 10. When the boiler-casing is in place, the flange 11 of its shell 5 fits over the bent upper edge 12 of the casing 11 of the firepot 9, as shown in Fig. 2. Now to 40 insure the maintenance of contact and a

close fit between the flange 11 and edge 12, I employ a yielding seal consisting of a continuous inwardly and downwardly projecting pressure-flange 13, turned inwardly from the upper edge of a sheet-metal band 14 attached by rivets 15 to the firepot-casing 10 and spaced therefrom by a reinforcing strap 16.

It will be readily understood that the pressure-flange 13 exerts a constant effort 45 to crowd the flexible sealing-flange 11 against the outer face of the upper edge 12 of the firepot-casing 10, and thus maintain a gas-tight joint between them. Furthermore, any gas which may escape between 50 these two surfaces is prevented from further escaping by the contact of the edge 13 with the exterior surface of the flange 11.

I claim:

1. The combination with a firepot having 55 a sheet-metal shell and a lining, of a removable boiler-casing comprising a sheet-metal shell, and a lining below the lower edge of which the shell extends to form a sealing-flange adapted to make close contact with the exterior surface of the upper edge of the firepot-shell, and an inwardly and downwardly projecting pressure-flange carried by the firepot and adapted to exert 60 a constant inward pressure upon the said 50 flange when the boiler-casing is applied to the firepot.

2. The combination with a firepot, having 65 a sheet-metal shell and a lining, of a removable boiler-casing comprising a sheet-metal shell and a lining below the lower edge of which the said shell extends to form a sealing-flange adapted to make close contact with the exterior surface of the upper edge of the shell of the firepot, a spacing 70 strap applied to the shell of the firepot, adjacent to the upper edge thereof, and an inwardly and downwardly projecting pressure-flange secured to the said strap, in position to exert a constant inward pressure 75 upon the said sealing-flange when the boiler-casing is applied to the firepot.

In testimony whereof, I have signed this specification in the presence of two subscribing witnesses.

JOHN PIERCE, Jr.
